UNITED STATES PATENT OFFICE.

FRED S. ENGLISH, OF NEW LONDON, CONNECTICUT.

INKING MECHANISM FOR PRESSES.

Application filed June 30, 1923. Serial No. 648,844.

To all whom it may concern:

Be it known that I, FRED S. ENGLISH, a citizen of the United States, and a resident of the city and county of New London, State of Connecticut, have invented certain new and useful Improvements in Inking Mechanism for Presses, of which the following is a specification.

My invention relates to inking mechanisms for presses and while I have chosen to illustrate the same embodied in two color rotary printing press wherein the advantages are greatest, nevertheless the invention is not limited to this adaptation.

There are several objects accomplished by the present invention. One object is to provide simple means for throwing out of operation as a unit all the form rollers so that they temporarily cease to supply ink to the form.

Another object is to provide means whereby the rollers may be inked up, i. e., the ink may be carried over to the form rollers, while the latter are separated from the form, preparatory to starting the printing run.

Another object is to provide means for controlling the distribution of the ink to suit almost any job which is to be run; that is to say, the inking mechanism may be so arranged that the newest supply of ink may be applied to any portion of the form, according to any special requirements of the form on which the sheets are to be printed. Or the new ink may be applied to the form just after a sheet has been printed or just before a sheet is about to be printed.

Another object is to provide simple means whereby when the inking mechanism has been temporarily moved away from the form it can be readily moved back or returned to exactly the same relation as before it was moved away, in order that when the proper relation or adjustment has once been determined for any job the parts can be easily restored to the same conditions after a stop such as at lunch hour or over night shut down. Other advantages will be made apparent in the following detailed description of my invention.

In the drawings forming part of this application,—

Figure 1 is a side elevation of part of a two revolution sheet feed rotary press to which my invention has been applied.

Figure 2 is an enlarged side elevation of the principal parts of the inking mechanism.

Figure 3 is an enlarged side elevation showing the device for throwing out the form rollers as a unit.

Figure 4 is a similar view showing the parts when the form rollers are actually thrown out, and

Figure 5 is a sectional view taken on the line 5—5 of Figure 4.

In Figure 1 I have shown part of one of the side frames 23 of a printing press. There is a feed board 6 from which the sheet is fed to the first impression cylinder 9 and while the sheet is being carried around this cylinder it receives an impression from the form on the first form cylinder 8. Then the sheet transfers from the first impression cylinder 9 to the transfer cylinder 10 and from the latter it is transferred to the second transfer cylinder 11. While the sheet is traveling around the latter it receives an impression from the form on the second form cylinder 12 and after that the sheet is taken by the delivery device. These parts are common to a two color rotary press but it is to be understood that my invention may be applied to other kinds of presses. In this form of press the entire inking mechanism is duplicated for both form cylinders 8, 12 but as they differ only in their locations a description of one will answer for both and also for other adaptations.

The inking mechanism as a whole is mounted on a carriage, only one of the side frames 20 of which is here shown, it being understood that a duplicate of it is arranged at the opposite side of the press.

There is a hand wheel 85 on a stud 84 and on this stud there is a pinion 21, operating through the intermediate gear 22 on the stationary rack 22 whereby the inking mechanism carriage may be racked toward or from the plate cylinder 12, the carriage being mounted on a suitable track as in present practice.

There is a shaft 87 on the carriage, which has a gear 71 which meshes with and is driven by the gear 70 when the carriage is close up to the form cylinder 12. The gear 70 as is usual is operated from the gear (not shown) of the form cylinder 12. When the gears 71 and 70 are in mesh the inking mechanism is operated when the press

is operated but these gears may be separated as when the carriage is racked forward (to the left in the drawings) by means of the hand wheel 85.

- 5 The gear 71 operates a gear 72 on the stud 1, and a small gear 75 on this same stud operates the gear 76 on a shaft 74, which latter makes one revolution for each complete cycle or operation of the press. There is a 10 cam 81 on the shaft 74 which operates on the roller 24 to rock the lever 80 on its shaft 25 and the lever 80 acts through the pitman 79 to rock the lever 26 on the shaft 78. The upper, forked end 27 of the lever 26 15 carries the shaft of the fountain ductor roller 68. This roller alternately contacts with the fountain roller 69 which takes the ink from the fountain 28, and with the vibrator roller 67. There is a crank 77 on 20 the shaft 74 and this operates through a pitman 29 to rock the lever arm 30 to actuate the fountain roller in the usual manner.

- The vibrator roller 67 transfers ink to both composition rollers 66 and these in turn 25 transfer ink to the ink drum 65 where it is further cut up. In the construction shown and which forms the feature of another application Serial No. 648,842, there are several (two as shown) ductor rollers 63, 64 30 which receive ink from the ink drum 65. The upper ductor roller 64 transfers ink periodically to the vibrator roller 62^a which in turn transfers the ink to the upper pair of form rollers 61. All the form rollers 35 contact with the form on the cylinder 12 when the press is in operation.

- The gear 72 on the stud 1, operates a gear 2 on the shaft 102 of the ink drum, whereby the latter is driven. The gear 2 operates the gears 73, which in turn operate gears 3 45 on the shafts of the vibrator rollers 62^a, 62^b.

- 45 There is a lever 112 rocking on the shaft 113 which has one arm provided with a roller 119, that is acted on by a cam 114 on the shaft 74 to operate this lever. The other 50 arm of this lever extends upwardly and it serves to move the ductor rollers 64, 63 into and out of contact with the vibrator rollers 62^a, 62^b; but this feature is fully described in the said copending case. It is sufficient to 55 point out that this lever 112 causes the ductor rollers to move in a planetary way back and forth partly around the ink drum 65, so that they periodically contact with the vibrators 62^a, 62^b and then move out of 60 contact.

- 65 Regulation of distribution of ink. It is evident that the ductor rollers 63 and 64 can be moved against the vibrators 62^a, 62^b, at any predetermined time depending on the time best suited to the job; that is, on the

period or places where the fresh supply of ink should be first applied to the particular form for best results. For instance, the fountain ductor roller 68 may put ink on the vibrator roller 67 just long enough before the roller 64 leaves the vibrator 62^a so that the fresh supply of ink is carried around on the drum 65 to the roller 64 but before the roller 62^a receives this fresh supply of ink. This can be controlled by a suitable setting of the cam 81 and the cam 114. When this has been done the relation of the time that the roller 64 comes back into contact with roller 62^a with a fresh supply of well cut up ink, to the timing of the form cylinder can be controlled by moving forward the carriage to release gear 71 from gear 70, and turning the press around until the form cylinder 12 is in position to receive the fresh supply of ink where most 80 desired. It may be desirable to have this fresh supply applied to the form during the first revolution in a cycle of the form cylinder 12 past the form rollers 61, or just after a sheet has been printed. If this is done, 85 then the ductor rollers 63 and 64 move away from the vibrators 62^a, 62^b during the next or second revolution of the form cylinder 12, and the ink which was placed on the form is further spread out. Or, the fresh 90 supply of ink can be put on the plate or form during the second revolution of the form cylinder of each cycle or just before a sheet is to be printed, and in time for the fresh supply of ink to cover the entire form 95 or set of plates. Or, the parts can be so timed that the fresh supply of ink is applied to one set or section of plates, which may be the first or last part of the whole form, when one section of the plate or form 100 requires less ink than another part,—so that, by simply racking the carriage forward or to the left in the drawings, far enough to separate the gear 71 from the gear 70 and by turning the plate cylinder 12 to the right 105 position the fresh supply of ink can be applied whenever and wherever desired to the plate or form. The carriage is also moved forward when access is to be had to the plate cylinder 12, and at other times and on 110 such occasions the gears 71, 70 are also separated, and I provide simple means for returning the gears 71, 70 back into the relation which was selected as the preferred one, whatever the reason may have been for 115 separating them, in order to continue the job under uniform conditions. For this purpose I provide a pointer 120 on the shaft 74 and there is a stationary index disk 121 attached to the carriage frame. By means 120 of the set screw 120' the pointer 120 may be set at any position on the shaft 74. This shaft 74, it is to be remembered, makes one revolution for each complete cycle or for each impression.

Another pointer 31, is placed on some member which makes one revolution per cycle and from which the carriage is disconnected when moved forward. I have shown such a pointer 31, attached to the shaft 32 of the press in Figure 1, and there is an index plate 33 fixed near the path of this pointer. When the parts are originally set for the desired distribution of ink, the pointers 120 and 31 are set at the marks on their respective indexes and whenever the carriage has been racked forward and it is to be returned again, it is only necessary to see that the pointers 120 and 31 point to the marks on their indexes and then if the carriage is moved back into place the gears 71 and 70 will come into mesh in the same relation as before and the distribution of ink will continue to be the same as before the carriage was moved. In bringing the pointer 120 into line with its index mark, the operator may rotate the ink drum 65 and he may turn the press around to bring the pointer 31 into line with its index mark. The drum ductor rollers 64, 63 facilitate in arriving at the adjustments of distribution above pointed out.

The ink rollers may be inked up before starting to ink the plate or before feeding the sheets to the press. The carriage may be racked forward or to the left to disengage the form rollers 61 from the form or plate of the cylinder 12, but the gears 71, 70 remain about half in mesh. In this condition the press may be operated and the entire set of rollers will be driven just as if the press were printing but the form rollers 61 will not place ink on the plate or form. While the weight of the parts will hold the carriage in this position, I have shown a hook 123, engaging a pin 123^a on the carriage to prevent the gears 71, 70 from getting entirely out of mesh.

The form rollers 61 may be thrown out as a unit where the press is to be stopped for any length of time, such as during lunch hour. The form roller socket 124 is of the usual type and for simplicity I have shown only one of these in Figure 4, but it will be understood that each roller should have a socket. These sockets are all attached to a circular segment 125 which is formed on an arc the center of which is the axis of the cylinder 12 when the carriage is close up or in printing position relatively to this cylinder 12. This segment is in the nature of a lever pivoted on the stud 126 so that it can swing toward and from the cylinder 12.

There is a shaft 127 extending across the press just above the form rollers, and it is supported or journaled in a hub 128 on the carriage. The segmental lever 125 has a fork 129 at its upper end and cooperating with this fork there is an eccentric bushing 130 which is pinned to the shaft 127 and it

extends into the fork 129 and is provided with a flange 131 to prevent lateral movement. On the end of the shaft 127 there is a handle 132 and to the inside of it there is a stop lever 133 which limits the rotation of the shaft to about one half revolution. When the handle 132 is placed as shown in Figure 4, the segmental lever 125 is swung over on the stud 126 so that all the form rollers 61 are held disengaged from the vibrator rollers 62^a, 62' and it is to be understood that at this time the carriage is racked forward so that the form rollers are also separated from the form or plate on the cylinder 12. When the handle 132 is moved to the position shown in Figure 3 all the form rollers are in contact with the vibrator rollers, 62^a, 62' and they are all equidistant from the plate cylinder or they lie in an arc which is concentric with the axis of this cylinder, when the carriage is moved up close to the cylinder with the form rollers touching the form or in its path. When the press is stopped, the carriage is racked forwardly a few inches and the handle 132 is thrown over and the whole set of form rollers is out of contact with the form or plate.

Having described my invention, what I claim is:

1. In a press the combination of a press having a plate or form cylinder and a gear, a carriage movable toward and from said cylinder and having inking mechanism carried thereon, including a gear adapted to mesh with said first gear, indicating means associated with the inking mechanism on said carriage and indicating means associated with said press, whereby when said carriage is moved toward said cylinder said gears may be caused to mesh in predetermined relation.

2. In a press the combination of a press having a plate or form cylinder and a gear, a carriage movable toward and from said cylinder and having inking mechanism carried thereon, including a gear adapted to mesh with said first gear, indicating means associated with a member of the inking mechanism which makes one revolution per cycle of the press, and indicating means associated with a member of the press which makes one revolution per cycle of the press, whereby when said carriage is moved toward said cylinder said gears may be caused to mesh in predetermined relation.

3. In a press the combination of a press having a plate or form cylinder and a gear, a carriage movable toward and from said cylinder and having inking mechanism carried thereon, including a gear adapted to mesh with said first gear, an ink drum, form rollers, a ductor roller interposed between said drum and said form rollers for periodically transferring ink to the latter and indicating means associated with said press and

- with said inking mechanism for the purpose set forth.
4. In a press the combination of a press having a plate or form cylinder and a gear, 5 a carriage movable toward and from said cylinder and having inking mechanism carried thereon, including a gear adapted to mesh with said first gear, adjustable indicating means associated with the inking mechanism on said carriage, and indicating means associated with said press whereby when the carriage is moved toward said cylinder said gears may be caused to mesh in predetermined relation.
- 10 5. In a press the combination of a press having a plate or form cylinder and a gear, a carriage movable toward and from said cylinder and having inking mechanism carried thereon, including a gear adapted to 20 mesh with said first gear, indicating means associated with the inking mechanism on
- said carriage, and adjustable indicating means associated with said press whereby when the carriage is moved toward said cylinder said gears may be caused to mesh in 25 predetermined relation.
6. In a press the combination of a press having a plate or form cylinder, a carriage movable toward and from said cylinder, having inking mechanism carried thereon, 30 indicating means associated with the inking mechanism on said carriage and indicating means associated with the press whereby when said carriage is moved toward said cylinder its driving mechanism may be 35 properly timed with relation to said cylinder.

Signed at New London, county of New London, and State of Connecticut, this 31st day of March, 1923. 40

FRED S. ENGLISH.
